ENGINE STARTER GEARING

Daniel P. Kearney, Birmingham, Mich., assignor,
by scheme assignments, to Bendix Aviation Corporation,
South Bend, Ind., a corporation of
Delaware

Application August 31, 1937, Serial No. 161,780

8 Claims. (Cl. 74—7)

The present invention relates to engine starter gearing and more particularly to a transmission for automatically connecting a starting motor to a member of an engine to be started, and disconnecting the same when the engine becomes self-operative.

In gearing of the type indicated, it is desirable to provide some means for preventing the premature disconnection of the gearing occasioned by a false or abortive start of the engine. Inasmuch as engagement of the gearing is dependent on the acceleration of the starting motor, reengagement after disconnection requires that the starting motor be deenergized and allowed to come substantially to rest before it is possible to reengage the gearing and renew the attempt to start the engine. This is time-consuming and permits the engine to come to a complete stop before resuming the cranking operation which is sometimes disadvantageous.

It is an object of the present invention to provide novel starter gearing of the automatic mesh and demesh type including provisions for preventing the demeshing of the gearing until the engine has overrun the starting motor by a predetermined amount.

It is another object to provide such a device in which a starter pinion is positively held in mesh with an engine flywheel gear until the flywheel gear has overrun the starting motor by a predetermined amount of rotation.

It is a further object to provide such a device in which the holding means is arranged not to interfere with the action of the pinion during the meshing operation.

It is another object to provide such a device including an overrunning connection between the pinion and starting motor.

It is a further object to provide such a device in which the overrunning connection resumes the transmission of torque from the starting motor to the pinion as soon as the starting motor catches up with the speed of rotation of the pinion.

Further objects and advantages will be apparent from the following description taken in connection with the accompanying drawings in which:

Fig. 1 is a side elevation partly in section of a preferred embodiment of the invention illustrating the parts in their normal or idle position;

Fig. 2 is a similar view showing the parts in cranking position;

Fig. 3 is a similar view showing the parts in the positions assumed when the engine starts and

causes the driving pinion to overrun the starting motor;

Fig. 4 is a detail in perspective of the driving pinion and its overrunning clutch connection to the control nut, the parts being shown disassembled and partly broken away;

Fig. 5 is a detail in section of an embodiment of the invention incorporating a different form of overrunning clutch connection for the pinion; and

Fig. 6 is a view similar to Fig. 5 showing a further variation in overrunning clutch structure.

Referring first to Fig. 1 of the drawings, there is illustrated a power shaft 1 which may be the extended armature shaft of a starting motor, not illustrated. A hollow shaft 2 is fixedly mounted on the power shaft 1 by any suitable means such as a key 3, and a screw shaft 4 is freely journaled on the hollow shaft 2, being retained thereon by suitable means such as a stop nut 5.

Means for yieldably driving the screw shaft 4 from the hollow shaft 2 are provided in the form of a torsion spring 6 anchored as by means of a stud 7 to an enlarged portion 8 of the hollow shaft, the opposite end of the spring being attached by means of a stud 9 to an enlarged end portion 11 of the screw shaft.

A driving member in the form of a pinion 12 is freely journaled on the power shaft 1 for longitudinal movement into and out of engagement with a member such as a flywheel gear 13 of an engine to be started. Means for traversing the pinion into and out of engagement with the engine gear and for rotating the same are provided in the form of a control nut 14 mounted on the screw shaft 4 for threaded engagement therewith and connected by means of an overrunning clutch member 15 to a barrel member 16 which is rigidly connected in any suitable manner as indicated at 17 to the pinion 12.

As here illustrated, the overrunning clutch connection between the control nut 14 and the barrel 16 is effected by forming complementary teeth 18 and 19 (Fig. 4) on the clutch member 15 and control nut 14 respectively, the clutch member 15 being non-rotatably connected to the barrel 16 as by means of lugs 21 on the barrel traversing openings 22 in the clutch member, and a retaining spring wire 23 seated in complementary grooves 24 and 25 in the clutch member and barrel respectively.

Means are preferably provided for limiting the separation of the control nut 14 from the clutch member 15, such means being here shown in the

form of a ring or thimble 26 mounted on the control nut 14 and having a lock ring 27 seated in the interior thereof in position to engage the rear face of the clutch member 15.

5 In order to prevent rebounding of the pinion into engagement with the engine gear after being demeshed therefrom, the threads of the screw shaft 4 are preferably terminated adjacent the idle position of the control nut 14, forming a smooth portion 28 (Fig. 2) on the screw shaft 10 on which the control nut may rotate freely when in idle position. Means in the form of a compression spring 29 are provided for causing the control nut 14 to enter the threads of the screw shaft when the screw shaft is accelerated by the 15 starting motor.

Means in the form of a light compression spring 31 mounted in the barrel 16 between the stop nut 5 and the clutch member 15 are provided for urging the pinion and barrel assembly 20 toward idle position and preventing it from drifting toward cranking position during operation of the engine.

In the operation of the starting mechanism as 25 so far described, acceleration of the screw shaft 4 by means of its connection to the power shaft 1 when the starting motor is energized causes the control nut 14 to thread itself along the screw shaft into the position illustrated in Fig. 2, causing the driving pinion 12 to mesh with the engine gear 13. When the longitudinal movement of the control nut 14 is stopped by the stop nut 5, the parts are all connected for rotation from the power shaft 1 through the spring 6 and overrunning clutch member 15, whereby the pinion 12 is rotated to crank the engine. It will be noted that at this time the clutch member 15 is clamped tightly against the control nut 14 by reason of the engagement of the flange 32 on the clutch member 15 against the thrust washer 33 which is seated against the stop nut 5. The pitch of the threads of the screw shaft and control nut is comparatively steep so as to cause the driving pinion to be meshed with the engine gear by the initial rotative movement of the screw shaft, and to avoid wedging or locking up of the pinion in driving position.

When the engine starts, the acceleration of the engine gear 13 due to the self-operation of the engine causes the pinion 12 to overrun the starting motor whereby the control nut 14 is rotated through the barrel 16 faster than the screw shaft 4, causing it to back away from the clutch member 15 and permit the pinion, barrel 50 and clutch member to overrun. If the engine continues to be self-operative, the overrunning action of the pinion and barrel assembly, together with the expansion of the return spring 31 causes the control nut 14 to be moved back 55 on the screw shaft 4 to its idle position where it rotates freely on the smooth portion 28 of the screw shaft until the parts come to rest.

According to the present invention, means are provided for positively maintaining the pinion 12 in engagement with the engine gear 13 until the pinion has been caused to overrun the starting motor a predetermined number of revolutions, thus preventing disengagement of the gearing due to a false or abortive start of the engine, and permitting such disengagement only 65 in case of a true initiation of self-operation of the engine.

As here illustrated, this means is in the form of a latch member 34 hinged to the stop nut 5 70 as illustrated at 35 and yieldingly urged against

the interior of the barrel 16 as by means of a spring 36. The interior of the barrel 16 is provided with a spiral groove 37 of suitable low pitch in which the nose of the latch 34 is adapted to engage when the pinion is moved toward operative position as illustrated in Fig. 2. The barrel 16 is formed with a smooth portion 38 for receiving the latch 34 when the barrel is in idle position so as to permit the barrel and pinion assembly to then overrun freely.

10 In operation, during the meshing movement of the pinion and barrel assembly by the traversal of the control nut 14 on the screw shaft, the latch 34 ratchets over the convolutions of the spiral groove 37 without interfering with the 15 meshing movement of the pinion 12. When an explosion occurs in the engine, the acceleration of the driving pinion 12 by the flywheel gear causes the pinion and barrel assembly to overrun the screw shaft, whereby the control nut 14 is 20 caused to back away as previously described. The latch 34 prevents immediate withdrawal of the pinion 12 so that the control nut 14 moves away from the clutch member 15, thus permitting the pinion and barrel assembly to overrun the 25 control nut. If the engine continues to operate under its own power, the barrel 16 continues to overrun and thread itself back on the latch 34 until after a predetermined number of revolutions the pinion 12 is completely demeshed from 30 the engine gear. If, however, the start of the engine should be abortive so that the overrunning action of the pinion and barrel assembly 35 is discontinued before the predetermined number of revolutions has been accomplished, the 40 slowing down of the pinion and barrel assembly will permit the control nut to pick up the clutch member 15 and cranking is resumed as soon as the starting motor catches up with the engine speed. It will be understood that the pitch of 45 the spiral groove 37 in the barrel is so selected that the predetermined number of revolutions necessary for demeshing the driving pinion is such as to effectively distinguish between a false and a true start of the engine.

45 In Fig. 5 an optional somewhat simplified form of overrunning clutch connection between the control nut 41 and overrunning clutch member 42 is provided. In this case the engaging clutch surfaces are coned slightly, the control nut 41 is mounted within the barrel 43, being retained 50 therein by a lock ring 44, and the connection between the clutch member 42 and the barrel is effected by means of radial lugs 45 on the clutch member extending into grooves 46 in the barrel. 55

In Fig. 6 the structure is substantially similar to Fig. 5 except that the engaging surfaces of the control nut 41 and clutch member 42 are formed without serrations, the necessary frictional driving connection being effected by the selection of 60 a suitable angle of inclination of these surfaces to the axis of the drive.

In Figs. 5 and 6 a plurality of latches 34 are illustrated, which latches may, as shown, be in stepped relation with respect to the spiral groove 65 37 so as to reduce the amount of lost motion between the barrel and stop nut.

70 Although certain forms of the invention have been shown and described in detail, it will be understood that other forms are possible and various changes may be made in the dimensions and arrangements of the parts without departing from the spirit of the invention as defined in the claims appended hereto.

75 What is claimed is:

1. In an engine starter, a power member, a driving member, means for moving the driving member into and out of engagement with a member of an engine to be started and for connecting the driving member for rotation by the power member, said connecting means including an overrunning clutch, and detent means for preventing disengagement of the driving member from the engine member until the driving member has overrun the power member for a predetermined number of revolutions, said detent means being arranged not to interfere with the engaging movement of the driving member.
2. In an engine starter drive, a power shaft, a pinion freely mounted thereon for movement into and out of engagement with a member of an engine to be started, means including a threaded connection of high pitch and an overrunning clutch for moving the pinion into operative position and rotating the same, and means including a spiral connection of low pitch between the pinion and power shaft for maintaining the engagement of the pinion with the engine member until the pinion overruns the power shaft a predetermined number of revolutions.
3. In an engine starter drive, a power shaft, a pinion freely mounted thereon for movement into and out of engagement with a member of an engine to be started, means including a threaded connection of high pitch and an overrunning clutch for moving the pinion into operative position and rotating the same, and means including a ratchet connected to the power shaft and having a spiral connection of low pitch with the pinion for maintaining the engagement of the pinion with the engine member until the pinion overruns the power shaft a predetermined number of revolutions.
4. In an engine starter drive, a screw shaft, a control nut threaded thereon, a stop member limiting longitudinal movement of the control nut, a drive pinion, connecting means whereby longitudinal movement of the control nut moves the pinion into and out of engagement with a member of an engine to be started, an overrunning clutch between the pinion and control nut, and means on the stop member cooperating with the connecting means to prevent movement of the pinion out of engagement with the engine member until the pinion has overrun the power shaft a predetermined number of revolutions.
5. In an engine starter drive, a screw shaft, a control nut threaded thereon, a stop member limiting longitudinal movement of the control nut, a drive pinion, connecting means whereby longitudinal movement of the control nut moves the pinion into and out of engagement with a member of an engine to be started including a barrel member, an overrunning clutch between the barrel member and control nut, and means on the stop member cooperating with the barrel member to prevent movement of the pinion out of engagement with the engine member until the pinion has overrun the control nut a predetermined number of revolutions.
6. In an engine starter drive, a screw shaft, a control nut threaded thereon, a stop member limiting longitudinal movement of the control nut, a drive pinion, connecting means whereby longitudinal movement of the control nut moves the pinion into and out of engagement with a member of an engine to be started including a barrel member, an overrunning clutch between the barrel member and control nut, said barrel having a spiral groove, and a latch on said stop member engaging in said spiral groove to hold the pinion in engagement with the engine member until the pinion has overrun the control nut a predetermined number of revolutions.
7. In an engine starter drive, a driving member, means for traversing the driving member into and out of engagement with a member of an engine to be started and for rotating the same, and means independent of said traversing means including a latch member having a spiral connection with the driving member for preventing withdrawal of the driving member from the engine member until the driving member has overrun the latch member a predetermined number of revolutions.
8. In an engine starter, a power shaft, a pinion slidably journalled thereon, means for sliding the pinion into and out of mesh with a member of an engine to be started, means including an overrunning clutch for connecting the pinion for rotation by the power shaft, and detent means preventing disengagement of the driving member from the engine member until the driving member has overrun the power shaft a predetermined number of revolutions.

DANIEL P. KEARNEY.
